Carl Reynolds, Jr., and Robert H. Anders, Birmingham, Mich., assignors to Avco Manufacturing Corporation, Cincinnati, Ohio, a corporation of Delaware

Application December 16, 1952, Serial No. 22,735

Term of patent 14 years

(Cl. D67—3)

To all whom it may concern:

Be it known that we, Carl Reynolds, Jr. and Robert H. Anders, citizens of the United States and residents of Birmingham, in the county of Oakland, State of Michigan, have invented a new, original, and ornamental Design for a Refrigerator Cabinet, of which the following is a specification, reference being had to the accompanying drawing forming a part thereof.

The figure is a perspective view of a refrigerator cabinet embodying our new design. The right side of the refrigerator cabinet, not visible in the drawing, is substantially the same as the left side which is shown.

We claim:

The ornamental design for a refrigerator cabinet, as shown and described.
